PACKER

Feri A. Thaheld, Dallas, Tex., assignor to The
Guiberson Corporation, Dallas, Tex., a corpo-
ration of Delaware

Application April 27, 1936, Serial No. 76,638

4 Claims. (Cl. 166—12)

This invention relates to new and useful im-
provements in packers.

One object of the invention is to provide an
improved well packer which may be readily low-
ered into the well casing and set at any desired
point therein.

An important object of the invention is to pro-
vide an improved well packer including an elastic
packing element which is confined at its ends,
10 with means for reinforcing the extremity of the
packing element, whereby the element will not
flow around its confining member when dis-
torted, thereby eliminating shearing off of the
extremity of the packing member.

15 Another object of the invention is to provide
an improved packer including a support having an
elastic packing element thereon, with means em-
bedded in the upper end of the element for rein-
forcing the same so as to positively fasten the
20 element to its support and prevent it from pulling
away from the same when under pressure.

25 A further object of the invention is to provide
an improved packer having an elastic packing ele-
ment which is so reinforced that the thickness
of the packing element may be materially re-
duced, whereby the annular space between the
30 element and the well casing is increased, which
provides a greater by-pass for fluid as the device
is lowered, and also reduces the amount of ma-
terial necessary in the construction of the ele-
ment.

35 A construction designed to carry out the in-
vention will be hereinafter described, together
with other features of the invention.

40 The invention will be more readily understood
from a reading of the following specification and
by reference to the accompanying drawing, in
which an example of the invention is shown, and
wherein:

45 Figure 1 is a transverse, vertical, sectional view
of the upper portion of a packer constructed in
accordance with the invention.

Figure 2 is a view, similar to Figure 1, and
showing the lower end of the packer.

50 Figure 3 is a partial transverse vertical sec-
tional view, showing the packer in its set position,
and

Figure 4 is a perspective view of the reinforcing
bushing.

55 In the drawing, the numeral 10 designates an
elongate tubular mandrel having an annular
valve 11 threaded on its upper end. The valve
is preferably made integral with an ordinary fish-
ing neck 12 and this neck is arranged to be con-
nected in the tubing string. The lower end of

the mandrel has the usual coupling collar 13
screwed thereon and thus, it will be seen that the
mandrel may readily be connected in an ordinary
string of tubing.

An elongate sleeve or shell 14 surrounds the
5 mandrel 10 and extends substantially the entire
vertical length thereof. The bore of the sleeve or
shell has a diameter which is greater than the
external diameter of the mandrel, whereby an
annular space or passage 14' is formed between 10
the mandrel and shell. The lower end of the
shell is threaded to receive a collar 15 and this
collar is provided with internal slots 16, which
are arranged to receive keys 17 formed on the
outer surface of the mandrel, whereby rotation 15
of the mandrel will impart a rotation to the shell.
The lower end of the collar 15 rests on a support
or recovery ring 18 which is preferably welded on
the mandrel just above the lower end thereof
(Figure 2). Thus, it will be seen that the shell 20
14 is supported on the ring which, in turn, is
fastened to the mandrel. With this arrangement,
when the mandrel 10 is lowered within a well
casing A, the shell will be lowered therewith. The
extreme upper end of the bore of the shell 14 is
25 bevelled as shown at 19 whereby a valve seat ar-
ranged to receive the valve 11 is formed. It is
obvious that when the valve 11 engages the seat,
the annular passage 14' is closed.

The upper end of the shell is formed with an 30
annular cap 20 which is preferably made integral
therewith, and this cap is provided with an inter-
nal annular recess 20'. A cone 21 surrounds the
shell 14 and is supported on an external annular
shoulder 21' which is formed on the outer surface 35
of said shell. It is noted that the cone 21 may
be slid upwardly on the shell but its downward
movement thereon is prevented by the shoulder.
An annular elastic packing element or sleeve 22
surrounds the mandrel between the cap 20 and 40
the cone 21. The upper end of this element en-
gages in the recess 20' in the cap while the lower
end thereof engages in a similar recess 23 formed
in the cone, whereby said packing element is con-
fined between the cone and cap. When the pack-
ing element is in its normal position, the cone 21
is resting on the shoulder 21' and the outer sur-
face of the packing element is in alignment with
the outer surface of the cap and cone, as is clearly
50 shown in Figure 1.

With the above construction it will be obvious
that when the cone 21 is held stationary and the
shell or sleeve 14 is moved downwardly, the cap
20 will distort the packing element 22 into en-
gagement with the wall of the casing A. Suitable 55

means may be employed for locking the cone 21 with the casing wall so as to make the same stationary, but I prefer to employ slips 24 which are slidably mounted on the cone. Each slip is carried by a resilient bar 25 which has its lower end secured to the lower end of a cage 26. The cage is slidably mounted on the shell 14 and is provided with a hook 27 which normally engages a gudgeon 28 which is made integral with and extends outwardly from the shell. One side of the hook 27 is open and by observing Figure 1 it will be seen that normally the cage is fastened to and moves with the shell 14. When in this position, the slips 24 are held at the lower end 15 of the cone 21 and are out of engagement with the wall of the casing A. The upper ends of friction springs 29 are secured to the upper end of the cage 26, while the lower end of these springs are fastened to a collar or ring 30 which is slideable on the mandrel 10. It is noted that the collar 30 is at a point below the recovery ring 18 on which the shell 14 is supported.

It is obvious that when it is desired to set the packer, it is merely necessary to rotate the mandrel 10 which will rotate the shell 14 through the keys 17 and slots 18 so that the gudgeon 28 is moved out of engagement with the hooks 27. As soon as this occurs, a downward movement of the mandrel will cause the valve 11 to engage 30 the valve seat 19 at the upper end of the shell so as to close the annular passage 14'. Continued downward movement of the mandrel 10 will then cause the shell 14 to move downwardly so that the cap 20 will exert a pressure against the packing element 22. During this time the cage 26 has been held stationary by the friction springs 29 and the slips 24 have been caused to ride upwardly on the cone 21, whereby said slips are expanded into engagement with the wall of the 40 casing A. Therefore, the slips will hold the cone 21 stationary and a downward pressure of the cap 20 upon the packing element 22 will distort said packing element into engagement with the wall of the well casing. It is noted 45 that the parts which have been described above are all of the usual construction and are, therefore, subject to variation.

It has been found that in packers of this type, the upper end of the packing element 22 has a 50 tendency to flow upwardly around the outer edge of the cap 20. When this occurs and the packer is raised, that portion of the packing element which has been distorted around the lower outer edge of the cap is sheared off or torn by contact 55 with the interior coupling of the well casing. Also, it has been found that although the packing element 22 is molded to the shell 14, the constant pressure when said packer is packed tends to press the packing element away from the shell. 60 In order to overcome the disengagement of the packing element from the shell, it has been the usual practice to form the packing element of a sufficient thickness or width so that its movement into engagement with the casing wall need only be very slight. When this is done the by-pass space for the fluid between the surface of 65 the packing element and the interior of the casing A is very small. Reduction of this by-pass space causes the packer to lower very slowly 70 through the well fluid in the casing and, therefore, it is advantageous that this space be as large as possible.

To overcome the above objections and disadvantages, an annular reinforcing bushing 31 75 is molded into the upper end of the packing ele-

ment 22. The bushing is preferably constructed of metal or other suitable material and includes a collar or ring 32 at its upper end. The lower end of the bushing is provided with an outwardly flared skirt 33 which is preferably made integral therewith. The collar is formed with internal screw-threads whereby the bushing may be threaded on the upper end of the shell 14 just below the cap 20. By observing Figure 1, it will be seen that the bushing is located so that the collar 32 is positioned within the annular recess 20' in the cap. The threads form a positive fastening means between the bushing and the shell. The flared skirt 33 of the bushing extends outwardly and is, of course, molded within the upper end of the packing element 22.

It will be seen that when the packer is set and the packing element 22 is distorted, the metallic bushing 31 will positively reinforce the upper end of said packing element and will prevent the same from flowing upwardly around the lower outer edges of the cap 20. This is true because the metallic bushing is positively fastened to the shell 14 and cannot be distorted. The bushing not only prevents this upward flow of the packing element, but will also, upon distortion of said element, prevent the inner periphery of the packing element from moving away from the shell 14. Therefore, it will eliminate the danger of the packing element being separated from its support. Although only one bushing has been shown in the upper end of the packing element 22, it is obvious that a similar bushing could be mounted within the recess 23 in the cone 21 whereby the lower end of the packing element 35 would be similarly reinforced. It is also pointed out that although the bushing 31 is shown as threaded upon the shell 14, any suitable means of fastening said bushing to said shell may be employed, as, for instance, the collar 32 may be 40 engaged between shoulders formed on the outer surface of the shell. It would be possible also to rivet or otherwise secure said bushing to the shell.

The provision of the bushing 31 also reinforces 45 the packing element and permits the same to be made narrower in width or thickness. Thus, since it is not necessary to employ a comparatively thick packing element, it is possible to enlarge 50 the annular space between the outer surface of said element and the inner wall of the casing A, whereby the by-pass space for the fluid may be greatly enlarged. This increase of the by-pass 55 permits more rapid lowering of the packer into the well casing.

What I claim and desire to secure by Letters Patent is:

1. A well packer including, a support, an elastic packing element mounted on said support, means for distorting the packing element into its packing position, and an annular flared reinforcing bushing within the packing element and secured to said support for preventing upward flowing of the element when the same is distorted.

2. A well packer including, a support, an elastic packing element on said support, means for distorting the packing element into its packing position, and an annular metallic bushing secured to the support and having an annular flared skirt molded within the packing element for preventing upward flowing of the element when the same is distorted.

3. A well packer including, a support, an elastic packing element on said support, means for

distorting the packing element into its packing position, and an annular metallic bushing threaded on the support adjacent the upper end of the packing element and having an annular flared skirt molded within the upper end of said element for preventing upward flowing of the element when the same is distorted, said flared skirt also serving to prevent separation of the packing element from the support.

10. 4. A well packer including, a support, an elastic packing element surrounding said support, an annular cap engaging the upper end of the ele-

ment, an annular confining member engaging the lower end of said element whereby the element is confined between the cap and said member, means for holding the lower confining member stationary, means for moving the cap downwardly to distort the packing element, and a metallic annular reinforcing bushing secured to the support just below the cap and having an annular skirt molded within the packing element for preventing upward flowing of the element when the same is distorted.
